THRESHOLD

Filed Feb. 10, 1930

UNITED STATES PATENT OFFICE

FRANK REESE, OF MINNEAPOLIS, MINNESOTA, ASSIGNOR TO REESE METAL WEATHER STRIP CO., OF MINNEAPOLIS, MINNESOTA, A CORPORATION OF MINNESOTA

THRESHOLD

Application filed February 10, 1930. Serial No. 427,355.

My present invention provides a simple and highly efficient threshold and flashing for cooperation with a door bottom weather strip to form a weather-tight joint between a 5 swinging door and floor or sill and for the disposal of water collected between the threshold and flashing.

To the above end, generally stated, the invention consists of the novel devices and 10 combinations of devices hereinafter described and defined in the claims.

In the accompanying drawing, which illustrates the invention, like characters indicate like parts throughout the several views.

15 Referring to the drawing:

Fig. 1 is a view in transverse vertical section showing the invention applied to a floor for cooperation with a weather strip on the bottom of a swinging door;

20 Fig. 2 is a view corresponding to Fig. 1 but showing another form of backing for the flashing;

Fig. 3 is a perspective sectional view of the threshold, some parts being broken away and 25 sectioned;

Fig. 4 is a perspective view showing a section of the flashing; and

Fig. 5 is a perspective view showing a section of the backing, as illustrated in Fig. 1.

30 The threshold, which is formed from a single piece of metal, comprises a flat top member 6 and inner, outer and intermediate supporting flanges 7, 8 and 9, respectively. These flanges 7, 8 and 9 extend the full length 35 of the top member 6, and the inner flange 7 is in the form of a relatively flat ogee curve the top of which is spaced from the inner edge of the top member to leave the same unobstructed and its bottom edge is substantial-

40 ly directly under said inner edge of said top member. The outer flange 8 is formed on a flat ogee curve, extends materially outward of the top member 6 and its top is spaced slightly inward from the outer edge of said 45 top member.

The intermediate flange 9 is formed with the flange 8, is located substantially midway between the bottom edges of the flanges 7 and 8 and is perpendicular to the plane of the top 50 member 6. The threshold is rigidly secured

to the floor 10 by long screws 11 which extend through holes in the top member 6 between the flanges 7 and 8 and their heads are countersunk so that they are flush with the upper face of said top member.

Formed in the lower edge of the supporting flanges 7, 8 and 9 is a plurality of longitudinally spaced weep holes 12 and it is important to note that said holes in the several supporting flanges are staggered so that there will not be a direct draft therethrough.

55 A relatively wide thin metal flashing 13, in the form of a flat plate, is nailed or otherwise rigidly secured to the floor 10 under the threshold and all three supporting flanges 7, 8 and 9 rest directly thereon. The inner edge portion of the flashing 13 is turned into an upright position to afford a flange 14, the upper edge portion of which is rolled toward the threshold and downward out of contact 60 with the top member 6 and supporting flange 7.

65 Fig. 2 is a view corresponding to Fig. 1 but showing another form of backing for the flashing;

70 Fig. 3 is a perspective sectional view of the threshold, some parts being broken away and sectioned;

75 Fig. 4 is a perspective view showing a section of the flashing; and

Fig. 5 is a perspective view showing a section of the backing, as illustrated in Fig. 1.

80 The threshold, which is formed from a single piece of metal, comprises a flat top member 6 and inner, outer and intermediate supporting flanges 7, 8 and 9, respectively. These flanges 7, 8 and 9 extend the full length

85 of the top member 6, and the inner flange 7 is in the form of a relatively flat ogee curve the top of which is spaced from the inner edge of the top member to leave the same unobstructed and its bottom edge is substantial-

90 ly directly under said inner edge of said top member. The outer flange 8 is formed on a flat ogee curve, extends materially outward of the top member 6 and its top is spaced slightly inward from the outer edge of said top member.

95 The intermediate flange 9 is formed with the flange 8, is located substantially midway between the bottom edges of the flanges 7 and 8 and is perpendicular to the plane of the top member 6. The threshold is rigidly secured

flange 14 is spaced from the weather strip 23 to leave clearance therebetween.

In case condensation forms on the inner side of the door 22 the same will run down thereon follow the under side of the weather strip 23 and drip between the flanges 7 and 14 where the same is collected and will escape over the flashing 13, which projects the underlying floor 10, through the weep holes 12 to the outside of the building. The moldings 15 and 16 in addition to protecting the flange 14 by forming a rigid backing therefore to prevent the same from being bent or otherwise damaged, gives the threshold a neat and finished appearance.

15. What I claim is:

1. A threshold having inner and outer supporting flanges the former of which at its junction with the threshold is laterally spaced from the inner edge of the threshold, the outer face of the inner flange at the bottom edge thereof is substantially directly under the inner edge of the threshold, and a flashing under the threshold and extending outward of its two flanges, said flashing having at its inner edge a perpendicular flange with which the inner flange of the threshold engages to position the threshold on the flashing.
2. The structure defined in claim 1 which further includes a removable backing for the flange of the flashing entirely inward thereof, and means for securing the backing to a floor.
3. A flat flashing resting directly on a floor throughout its entire width and having an upstanding flange at its inner longitudinal edge, and a backing for the flange supported directly on the floor entirely inward of the flange and secured to the floor, in combination with a threshold supported directly on the flashing.

In testimony whereof I affix my signature.
FRANK REESE.
